CRATER CATHODE

George S. Evans, East Orange, N. J., assignor to
 Westinghouse Electric & Manufacturing Company,
 East Pittsburgh, Pa., a corporation of
 Pennsylvania

Application May 26, 1938, Serial No. 210,185

5 Claims. (Cl. 250—27.5)

My invention relates to gaseous electric discharge devices and, in particular, to such discharge devices embodying cathode structures adapted to provide copius supplies of ionized gas 5 in the region adjacent the cathode surface.

One object of my invention is to provide a cathode structure in which a partially enclosed region is provided about a thermionically emissive cathode surface, this region being especially 10 adapted to maintain a high degree of ionization in a gas or vapor within its confines.

Another object of my invention is to provide a cathode structure with means for constantly maintaining a higher pressure of a gas or vapor 15 in the region of the cathode surface than in the vicinity of an anode and/or a control electrode within a gaseous discharge tube.

Still another object of my invention is to provide a cathode structure adapted to continually supply a stream of gas or vapor drawn from a reservoir of liquid material within an electrical 20 discharge tube to the region about a thermionically emissive cathode surface.

Still another object of my invention is to provide an electrical discharge tube structure 25 adapted to establish paths of circulation in which a liquid is vaporized, the vapor conducted to a restricted region about a thermionically emissive cathode surface, is then conducted away 30 from this region, recondensed and returned to the aforesaid liquid.

Other objects of my invention will become apparent upon reviewing the following description taken in connection with the drawing, in which: 35 Figure 1 is a view, partly in elevation and partly in section, of one type of tube embodying the principles of my invention; and

Fig. 2 is a similar view of another type of tube embodying the principles of my invention.

My copending application Serial No. 210,184 discloses certain types of cathode structure which are adapted to provide a highly ionized body of vapor at a substantial pressure in an enclosure, the walls of which are heated to a thermionically emissive temperature, while at the same time maintaining a relatively low vapor pressure in the vicinity of the anode and control electrodes cooperating with said cathode. Where tubes are designed for large current outputs 40 capacities, the problem of fabricating the vacuum-tight containers for employing such cathodes is not a simple one, and I herein enclose structures particularly adapted for that purpose. Briefly stated, the container wall in the region 45 of the cathode is formed of sheet metal which is

sealed to the glass or other insulator which electrically separates the control electrode and anode of the tube from the cathode. By such an arrangement, the somewhat elaborate structure of the cathode chamber may be fabricated and 5 installed in the metallic portion of the tube wall before the glass insulation is put in place.

Referring particularly to Fig. 1, the portion of the tube in the neighborhood of the cathode comprises a metallic cup 1 which may be of iron 10 or any other metal having a suitably high melting point. If ordinary metals are employed for the cup 1, the portions thereof to which glass insulators are intended to be sealed should be made of some metal or alloy known in the art to successfully form vacuum-tight seals with the glass or other insulation employed. For example, if the insulation is the borosilicate glass commonly known as G702P, the portions of the metallic cup which are expected to form vacuum-tight 15 seals therewith may consist of the alloy Kovar, which is described in Patent No. 1,942,260 to Howard Scott and assigned to Westinghouse Electric & Manufacturing Company, of East Pittsburgh, Pennsylvania. As is well known in 20 the art, the alloy Kovar may be welded to the remainder of the metallic cup 1 by conventional methods, or, alternatively, the entire cup 1 may 25 itself consist of Kovar.

Within the metal cup 1, I support a heating device 3 in the form of a hollow cylinder which may consist of any suitable insulating refractory material. For example, the cylinder 3 may be molded from a mixture of barium and strontium oxides by methods well known in the art; alternatively it may be molded from zircon and then sintered. In good heat-conducting relation to the cylinder 3, preferably imbedded in its walls when it is molded, is a heater 4 which may be of nickel or of any other suitable resistance metal, 40 such as the alloy Konal described in Patent No. 2,030,112 to E. F. Lowrey and assigned to the aforesaid company. The heater wire 4 has one end extended downward to make contact with a liquid which partially fills the cup 1 and which will be more fully described later, and the other end passes through the wall of the metallic cup by an insulating seal made by methods well known in the tube art. For example, the seal 45 may consist of an insulating collar 5 of the adjacent boro-silicate glass which is sealed to the alloy Kovar on the metal cup 1 about the periphery of the collar 5 and is sealed to a short section 50 of the same alloy Kovar which is inserted in the 55

lead from the heater 4 where it passes through the collar 5.

The cup 1 is provided with a re-entrant channel 6 which extends from the level of the partition 2 down to a point near the bottom of the cup 1. It may be found desirable in some cases to provide the partition 2 with a number of perforations 7. An inleading wire 9 for current to the tube may be welded to the cup 1 at any desired point thereon. When the tube is undergoing exhaust, there is introduced into it a suitable quantity of a conducting and readily vaporizable liquid 8 such as mercury and the level of this liquid is adjusted to such a height that it makes contact with the lower end of the heater 4 when the tube is in the position illustrated in the drawing.

When the cup 1 has been constructed in the above-described manner, the vacuum-tight enclosure may be completed by a wall 11 of any desired shape and material. As illustrated in Fig. 1, the wall 11 may suitably be formed of borosilicate G702P glass which may be sealed at 12 to the upper edge of the cup 1. Alternatively it may be of ordinary German glass or of lead glass. Anode 13 and a control electrode 14, both of conventional form, may be sealed by well known means through the wall 11. In some cases, it may be desirable that the wall 11, instead of being formed of glass or other insulating material, may be composed of the same metal as the cup 1 and, in fact, constitute a mere continuation thereof. In such a case, the inleading conductors to the anode 13 and control electrode 14 may be sealed vacuum tight through the container wall by providing suitable openings edged with Kovar in the latter, and sealing thereto collars of borosilicate or other glass very similar to the collar 5 already mentioned. The collars are sealed in turn to the inleading conductors. It is even possible to assemble the entire tube structure with its glass insulation loosely placed in position and to start the evacuation of the tube prior to sealing of the glass insulation to the metallic portions, if so desired. The actual completion of the sealing operation can be carried out during the heating of the tube on exhaust, which is a normal step in the customary procedure of tube evacuation. On the other hand, it may be desirable to seal the glass insulation to the metallic portions completely before evacuation is started.

Having assembled the tube structure above described, it may be exhausted to a high degree of vacuum by methods well known in the art, the liquid 8 being introduced, and the entire device sealed off from the pumps.

When current is supplied to the heater 4 from any suitable source, the surface of the liquid 8 immediately below the central core of cylinder 3 will be heated, and the vapor of the liquid 8 will flow upward through the central opening of cylinder 3 to be recondensed upon the walls of the container 11. It will then flow down the latter until it reaches the partition 2 which will cause it to flow into the side channel 6 and so back to the bottom of the cup 1. By regulating the height of the liquid 8 so that it stands nearer to the bottom of the cylinder 3, the density and degree of ionization of the vapor adjacent the interior wall of the cylinder 3 will be increased. Similar results will follow from increasing the amount of current through the heater 4. An increase in current in the latter will, of course, likewise increase the thermionic emissivity of the internal wall of the cylinder 3. By suitably adjusting the height of the liquid 8 at the time the tube is ex-

hausted and the size of the heater 4, and by suitably cooling the exterior of the container 11, the difference in vapor pressure between the interior of the cylinder 3 and the region of the container 11 surrounding the anode 13 and the control electrode 14 may be fixed at substantially any desired value.

Referring particularly to Fig. 2, the container 11, the anode 13, control electrode 14, the seals 5 and 12, and the heater 4 are similar to those already described for Fig. 1 and require no separate description. However, the structure of the cathode chamber differs from that of Fig. 1. This cathode chamber consists of a double-walled cylinder 15 which may be of some thin wall metal such as nickel. The lower portion of the inner cylinder 16 is of relatively restricted area, but it is provided with a shoulder 17 near its upper portion so that it forms a cup within which may be positioned a collar of refractory insulating material 18 in which is imbedded the heater 4. The collar 18 may, for example, consist of a molded mixture of barium oxide and strontium oxide or it may consist of some other refractory insulation, but, if the latter, its interior surface is preferably coated with either a layer of mixed barium and strontium oxides superposed on a coating of nickel or other metal, or it may be coated with a layer of these materials mixed and sintered with particles of some metal such as nickel. The aforesaid layer is thus constructed so that it will be a free emitter of electrons when it is heated by the heater 4. The upper and lower ends of the cylinder 15 are closed by partitions, and the entire interior of the resulting structure is exhausted to a high degree of vacuum to render it as good a heat insulator as possible. For the latter reason, the metal composing its walls should be as thin as possible and should preferably have as low an electrical conductivity as possible. The cylinder 15 is supported upon and connected to the metal cup 1 by supports 19 which leave relatively restricted channels between the central cylinder 16 and the space surrounding the outer cylinder 15.

Alternatively, the metallic cylinders 15, 16, 17 may be replaced by any other good heat insulator of substantially similar surface contour, since its functions are largely those of heat insulating the interior of the collar 18 from the space surrounding the cylinder 15 and of providing restricted passages through which liquid may flow from said interior of collar 18 to said exterior of cylinder 15. When the portion 15, 16, 17 is of metal, as described, the lower end of the heater 4 may be welded or otherwise electrically connected to the portion 17, and the heating current will then flow through the walls of the metallic cylinders and through supports 19 to inleading wire 9. On the other hand, if some form of refractory insulator is substituted for the member 15, 16, 17, it will be necessary to extend the lower end of the heater 4 sufficiently to connect it to the cup 1.

When the aforesaid tube is exhausted, it is filled to about the level indicated with a liquid 8 which may be mercury or some similar conducting liquid. The level of the mercury is made such that it rises slightly above the partition 17. When the proper current is supplied to the heater 4, the liquid within the cylinder 15 will be rapidly vaporized and will flow out through the restricted opening 21 in the upper face thereof to be recondensed upon the walls of the tube 11. From there, it will flow down again to the region within the cup 1 external to the cylinder 15. There will accordingly be a continual slow flow of the liquid 75.

8 through the openings in the supports 19 up through the central cylinder 16 in the heated cup formed by the refractory cylinder 18 and the partition 17. The size of the channels through 5 which this liquid flow takes place should be so proportioned that, when the heater 4 raises the interior face of the collar 18 to an electron-emitting temperature, the desired pressure difference will exist between the vapor inside the refractory 10 collar 18 and the region surrounding the anode 13 and the control electrode 14. Proper cooling of the outside of the container 11 will cause more rapid condensation of the emitted vapor and tend to increase the pressure difference between the 15 regions just mentioned.

By making the diameter of the cylinder 16 and the distance between the lower end of cylinder 16 and the bottom of cup 1 smaller, the conduction of heat from the interior of cylinder 18 to the 20 liquid 8 in the space surrounding cylinder 15 may be decreased to substantially any desired amount. It is accordingly possible to maintain substantially as high a vapor pressure inside the collar 18 as may be desired, while at the same time 25 maintaining a relatively cool liquid surface in the region surrounding the cylinder 15, and as a consequence of the latter, maintaining a relatively low vapor pressure in all portions of the container 11 except the interior of the refractory 30 collar 18.

To fully illustrate one specific embodiment of my invention, the container 11 may have an outside diameter of approximately 6 inches and an over-all height of approximately 5 inches. The 35 metallic cup 1 may be of sheet Kovar about .050 inch thick and have an external diameter of about $2\frac{1}{4}$ inches and be about $2\frac{1}{2}$ inches in height from its bottom to the seal 12. In Fig. 1, the refractory cylinder 3 may be about $\frac{3}{4}$ inch in outside diameter, $\frac{1}{8}$ inch in inside diameter and $\frac{1}{2}$ inch high. The heater wire 4 may be designed to carry about 11 amperes at about 5 terminal volts. The distance from the lower edge of cylinder 3 to the surface of the liquid 8 may be about $\frac{1}{2}$ inch, and the internal diameter of the 45 tube 6 may be about $\frac{3}{16}$ inch.

In Fig. 2, the collar 18 may have an external diameter of about $\frac{3}{4}$ inch and its orifice 21 have an internal diameter of $\frac{1}{4}$ inch and be $\frac{1}{2}$ inch high. Below said orifice the internal diameter of cylinder 18 may be $\frac{1}{2}$ inch. The internal cylinder 16 may be $\frac{3}{16}$ inch in diameter and its lower end be $\frac{1}{8}$ inch above the bottom of cylinder 1. The cylinder 15 may be $1\frac{1}{4}$ inches in diameter 50 and $1\frac{1}{2}$ inches high. The anode 13 and its leading wires and the lead 9 may be proportioned so that the average output current of the tube in each figure may be 4 amperes. The spacing between the lower end of the anode 13 and the 55 upper face of the refractory collar 18 in Fig. 2, or 3 in Fig. 1, may be about $2\frac{1}{2}$ inches. Such a tube will be adapted to operate on a line of about 60 110 terminal volts.

While I have described two specific embodiments of my invention, the principles thereof are of broader application which will be evident to those skilled in the art. I accordingly desire that the following claims shall be restricted only insofar as is necessary in view of their express 65 terms and of the limitations imposed by the prior art.

I claim as my invention:

1. In combination with a vacuum tight container comprising a cup-shaped metallic wall portion, an anode sealed thereto by vacuum-tight 70

insulation and a vaporizable liquid in said cup, a cathode structure comprising a heating resistor, a surface of thermionically-emissive material, in heat-receiving relation to said resistor and supported within said cup-shaped wall portion above said liquid, the mouth of said cup facing in such a direction that the vapor formed when said liquid is heated by said surface is constrained to flow from the vicinity of said surface to the region within said container in the neighborhood 10 of said anode, and walls forming a restricted channel through which the condensate from said vapor is constrained to flow back to the neighborhood of said cathode structure.

2. In combination with a vacuum-tight container comprising a cup-shaped metallic wall portion, an anode sealed thereto by vacuum-tight insulation and a vaporizable liquid in said cup, a cathode structure comprising a heating resistor, a surface of thermionically-emissive material in heat receiving relation to said resistor and supported within said cup-shaped wall portion above said liquid, the mouth of said cup facing in such a direction that the vapor formed when said liquid is heated by said surface is constrained to flow from the vicinity of said surface to the region within said container in the neighborhood of said anode, and a heat-insulating body separating said cathode structure from the walls of said container and forming a restricted channel through which 30 condensate of said vapor is constrained to flow back to said vaporizable liquid.

3. In combination with a vacuum-tight container comprising a cup-shaped metallic wall portion, an anode sealed thereto by vacuum-tight insulation and a vaporizable liquid in said cup, a cylindrical cathode structure comprising a heating resistor, a surface of thermionically-emissive material in heat-receiving relation to said resistor and supported within said cup-shaped wall portion above said liquid, an aperture through the mouth of said cup facing in such a direction that the vapor formed when said liquid is heated by said surface is constrained to flow from the vicinity of said surface to the region within said container in the neighborhood of said anode, and walls forming a restricted channel through which the condensate from said vapor is constrained to flow back to the neighborhood of 40 said cylindrical cathode structure.

4. In combination with a vacuum-tight container comprising a cup-shaped metallic wall portion, an anode sealed thereto by vacuum-tight insulation and a vaporizable liquid in said cup, a cathode structure comprising a heating resistor, a surface of thermionically-emissive material in heat-receiving relation to said resistor and supported within said cup-shaped wall portion above said liquid, the mouth of said cup facing in such a direction that the vapor formed when said liquid is heated by said surface is constrained to flow from the vicinity of said surface to the region within said container in the neighborhood of said anode, and a heat-insulating body separating said cathode structure from the walls of said container and forming a restricted channel through which condensate of said vapor is constrained to flow back to said vaporizable liquid.

5. In combination with a vacuum-tight container comprising a cup-shaped metallic wall portion, an anode sealed thereto by vacuum-tight insulation and a vaporizable liquid in said cup, a cylindrical cathode structure comprising a heating resistor, a surface of thermionically-emissive 75

material in heat-receiving relation to said resistor and supported within said cup-shaped wall portion above said liquid, the mouth of said cup facing in such a direction that the vapor formed when said liquid is heated by said surface is constrained to flow from the vicinity of said surface to the region within said container in the neigh-

borhood of said anode, and a heat-insulating body separating said cylindrical cathode structure from the walls of said container and forming a restricted channel through which condensate of said vapor is constrained to flow back to said vaporizable liquid. 5

GEORGE S. EVANS.
